UNITED STATES PATENT OFFICE.

FRANK PINK, OF PORTSMOUTH, ENGLAND.

SLEEPING BERTH FOR SHIPS, CARAVANS, RAILWAY CARS, AND THE LIKE.

Application filed July 5, 1924, Serial No. 724,437, and in Great Britain March 10, 1924.

The present invention relates to improvements in sleeping-berths for ships, caravans, railway cars, and the like.

In cases as in the smaller cabins on board ship, and particularly on yachts, the sleeping bunk is often used as a settee in the daytime. That which is soft enough to sit on is not comfortably soft to sleep on.

If however a spring mattress is used it is comfortable to sleep on, but yields too much to be comfortable to sit on.

The ordinary bunk has a lee-board or rail in front either extending the full length or part of the length of the bunk, to prevent the occupant from rolling out, and this does not improve the bunk if used as a settee.

The present invention broadly consists in a movable or false bottom, which may be padded, so arranged that when the berth is to be used as a settee, the false bottom can be raised up to form a support or backing close under the sleeping-mattress, which may be a woven wire or other kind of spring or canvas slung from end to end.

Any appropriate lifting and lowering device may be employed, as for example a screw device or a crank or eccentric device.

In one such device which will serve, the board is mounted on cranks which are connected to a lee-rail or board in front of the bunk, so that when the false bottom is up, the lee-rail or board is down, and when the mattress is in use for sleeping the lee-rail is automatically up.

The cranked part which holds the bed board may be set at right angles to an arm or lever which works the lee-rail or board; by raising the lee-rail and so giving that crank a quarter turn, the bed boards can be lowered sufficiently. Two cranks only need be connected to the lee-rail, as that is sufficient to work the apparatus. Other cranks can simply be attached to the bottom of the bed boards.

The accompanying drawings illustrate by way of examples two ways of carrying the invention into practical effect by a crank movement.

Fig. 1 is a front elevation, partly in section, of one form of apparatus.

Fig. 2 an end sectional view.

Fig. 3 is a diagrammatic view of a ship's sleeping-berth shewing the present invention applied to the bunk.

Fig. 4 is a front elevation of a modified form of lifting and lowering device, and

Fig. 5 an end view thereof.

Referring to Figs. 1 to 3, a readily yielding mattress *a*, as for example, a flexible wire mattress, is secured or slung in appropriate supports *b*, *c*, mounted on the ends *d*, *e*, of the sleeping berth.

f is a movable or false bottom adapted to be raised, as shewn in full outline to form a support or backing close under the sleeping-mattress *a*.

The device illustrated for lifting or lowering the false bottom *f* consists of bent rods *g* forming cranks *g*¹, *g*² and crank shafts *g*³, *g*⁴, mounted in bearings *h*, *i*, in the sides *k* and *l* of the berth. Any suitable number of these rods may be used, three are shewn. The false bottom *f* is mounted on the rods *g* and is given an up and down movement through the mediation of bearings *m*, on the underside of the false bottom *f*.

Each crank shaft *g*³ is extended in alignment with the crank *g*¹ to form an arm *n* to which the lee-rail or board *o* is pivoted.

As shewn in the drawings the false bottom *f* is raised close to the mattress *a* so that the bunk may be used as a settee. When however the cranks are given a half turn the false bottom is lowered out of use, and rests on a base or support *p*, while the lee-rail or board *o* is simultaneously raised to its normal position as shewn in dotted outline.

Stops or clips *q* may be provided to prevent the lee-rail, when this is down, from being accidentally moved. When the lee-rail is to be raised it is released from the stops or clips *q* by a slight forward movement.

In the modified form shewn in Figs. 4 and 5, the straight part of the rod *g* which carries the false bottom *f* is set at right angles to the extension or arm *r* on which the lee-rail or board *o* is pivoted, so that a lesser angular turn than that given to the form shewn in Fig. 1 effects the desired movement of the false bottom and lee-rail.

When the bunk is in use as a settee the cranks *g* may be turned slightly beyond the dead centre as shewn in Fig. 4, and the lee-rail brought against a stop *s* so that accidental movement of the bottom from its raised position is prevented.

The bottom of the bed board may be grooved or recessed, and the cranked parts arranged to slide therein, so that endwise movement of the bed board when this is being lowered does not take place.

In the arrangement shewn by Figs. 1 and 2 it will be observed that the false bottom is functioning as a support and the lee-rail is out of use when the cranks are at the 10 twelfth hour and the false bottom is in an inoperative position and the lee-rail positioned for use when the cranks have been moved to the sixth hour. In Figs. 4 and 5 the false bottom is functioning as a support and the lee-rail is out of use when the cranks are pointing to the eleventh hour and the false bottom is in an inoperative position and the lee-rail positioned for use when the cranks have been moved to the 20 third hour. In this arrangement the crank has a movement beyond the dead centre position which movement is limited by the stop s.

What I claim is:—

1. A berth convertible into a seat, comprising in combination a readily yielding mattress, a false bottom arranged to reinforce the mattress when the berth is to be used as a seat, a lifting and lowering device for said bottom, and a lee-rail, means connecting the bottom with the lee-rail so that when the bottom is raised close up to the mattress the lee-rail is out of normal position and when the bottom is withdrawn from the mattress the lee-rail is simultaneously returned to normal position.

2. A berth convertible into a seat comprising in combination a readily yielding mattress, a false bottom arranged to reinforce the mattress when the berth is to be used as a seat, a crank device on which said bottom is mounted and a lee-rail, means connecting the crank device with the lee-rail so that when the bottom is raised close up to the mattress the lee-rail is out of normal position and when the bottom is withdrawn from the mattress the lee-rail is simultaneously returned to normal position.

3. A berth convertible into a seat comprising in combination a readily yielding mattress, a false bottom arranged to reinforce the mattress when the berth is to be used as a seat, cranks on which said bottom is mounted and a lee-rail, means connecting the cranks with the lee-rail so that when the

bottom is raised close up to the mattress the lee-rail is out of normal position and when the bottom is withdrawn from the mattress the lee-rail is simultaneously returned to normal position, said cranks moving beyond the dead centre position when raising the said bottom, and means for preventing accidental movement of the bottom from its raised position.

4. A berth convertible into a seat comprising in combination a readily yielding mattress, a false bottom arranged to reinforce the mattress when the berth is to be used as a seat, cranks on which said bottom is mounted and a lee-rail, means connecting the cranks and the lee-rail so that when the bottom is raised close up to the mattress the lee-rail is out of normal position and when the bottom is withdrawn from the mattress the lee-rail is simultaneously returned to normal position, said cranks moving beyond the dead centre position when raising the said bottom, and a stop co-operating with the lee-rail for preventing accidental movement of the bottom from its raised position.

5. A berth convertible into a seat comprising in combination a readily yielding mattress, a false bottom arranged to reinforce the mattress when the berth is to be used as a seat, cranks on which said bottom is mounted, a crank shaft, an extension thereof, and a lee-rail pivoted to said extension, means connecting the cranks with the lee-rail so that when the bottom is raised close up to the mattress the lee-rail is out of normal position and when the bottom is withdrawn from the mattress the lee-rail is simultaneously returned to normal position.

6. A berth convertible into a seat comprising in combination a readily yielding mattress, a false bottom arranged to reinforce the mattress when the berth is to be used as a seat, a lifting and lowering device for said bottom, and a lee-rail, means connecting the bottom with the lee-rail so that when the bottom is raised close up to the mattress the lee-rail is out of normal position and when the bottom is withdrawn from the mattress the lee-rail is simultaneously returned to normal position, and means for preventing the lee-rail when out of normal position from being accidentally moved.

In testimony whereof I affix my signature.

FRANK PINK.
